UNITED STATES PATENT OFFICE.

SAMUEL L. DENNEY, OF STRASBURG, ASSIGNOR OF ONE-FOURTH TO ISRAEL L. LANDIS, OF LANCASTER, PENNSYLVANIA.

CAR-DOOR FASTENER.

SPECIFICATION forming part of Letters Patent No. 281,246, dated July 17, 1883.

Application filed May 24, 1883. (No model.)

To all whom it may concern:

Be it known that I, SAMUEL L. DENNEY, a citizen of the United States, residing at Strasburg, in the county of Lancaster and State of Pennsylvania, have invented certain new and useful Improvements in Fasteners for Car-Doors, of which the following is a specification, reference being had therein to the accompanying drawings.

10 My invention relates to improvements on fastenings for sliding doors on railroad-cars; and the peculiarity consists in securing the door at the rear by means of a lever so pivoted in suitable jaws and acting against a corresponding-shaped catch or stop, which tends to force the door firmly against the jamb and also against the side of the car. I also include the staple, which is so constructed as to be turned in its berth after the slotted end of the lever 15 has been forced down over it, thereby holding the lever securely in place.

The details of construction and operation of the several parts will be more fully set forth in the claims, and shown in the accompanying drawings, in which—

20 Figure 1 is a side elevation of a car-door with the locking device attached thereto, the door being closed and locked. Fig. 2 is a horizontal section on the line A B, Fig. 1. Fig. 3 is a perspective view of the staple detached; and Fig. 4 is a rear view of the staple and its berth, in which it works.

25 Referring more particularly to the drawings, C represents the side of the car provided with its side rails, E, which have guides F secured to and projecting above and below the rails.

To the inside of the door is fastened a piece, D, in the form somewhat of the section of a hinge, with suitable jaws projecting in rear of the door, in which is pivoted lever L, the forward end being provided with a slot to receive the staple K, and the rear end with a curved form to take hold of a corresponding-shaped catch, H, which is embedded in and extends 30 through the side of the car from the inside.

40 By turning the lever out at a right angle with the door the curved end of same enters into a slot formed in the piece to which it is pivoted, thereby allowing the door to slide freely in its

ways in opening or closing. The peculiar 50 shape of the lever and the catch with which it engages has the effect to force the door firmly up to the jamb, and also to draw the door tight against the side of the car, that rain, snow, or sparks may not enter, as is now 55 the case.

I construct my staple of three parts or separate pieces. The first consists of a flange, o, with a boss, which extends through the thickness of the door, as shown in Fig. 2. Said 60 piece is provided with a hole to receive the stem of the staple proper, as shown in Fig. 3. Said staple is slotted to receive the lock or seal, and has a heavy side, which, in connection with the little crank at its opposite end, 65 will keep it in the position shown in Fig. 3.

In constructing the staple the stem is inserted in the piece in which it works, and the crank is then riveted fast to the stem. A quadrant-shaped recess, S, is provided for its 70 reception. Thus it will be seen that by taking hold of the staple and turning it to a horizontal position the slot in the lever will pass over and against the car-door. Then the staple, of its own gravity, will return to its vertical position, and standing across the slot in the lever securely confines it in its place.

Having thus described my invention, what I claim is—

1. A fastening for sliding doors, consisting 80 of a bent and curved lever secured to the edge of the door, an opening in the side of the car, into which the end of the lever extends in the locked position, and means for securing the other end of the lever, all as set forth. 85

2. A fastening for sliding doors, consisting of a bent and curved lever secured to the edge of the door, an opening in the side of the car, into which the end of the lever extends in the locked position, the outer end of the lever 90 being provided with an opening, and an oscillating or rotating headed bolt to engage therewith and hold the lever in a locked position, as set forth.

3. In a car-door fastening, the combination 95 of the plate D, secured to the door at one edge thereof, and provided at one end with jaws and near the other with an oscillating headed

bolt or staple, K, and the curved and bent lever L, pivoted between the jaws of the plate D, its inner end arranged to engage with a recess in the side of the ear, and its outer end having an opening for the reception of the bolt by which it is secured in its locked position, as set forth.

In testimony whereof I affix my signature in presence of two witnesses.

SAMUEL L. DENNEY.
